UNITED STATES PATENT OFFICE.

WALTER CAVE, OF LONDON, ENGLAND, ASSIGNOR TO CARL BECHSTEIN, OF SAME PLACE AND BERLIN, GERMANY.

DESIGN FOR A PIANO-CASE.

SPECIFICATION forming part of Design No. 24,805, dated October 29, 1895.

Application filed December 15, 1894. Serial No. 531,972. Term of patent 14 years.

To all whom it may concern.

Be it known that I, WALTER CAVE, a subject of the Queen of Great Britain and Ireland, residing at London, England, have invented and produced a new and original Design for Pianoforte-Cases, of which the following is a specification, reference being had to the accompanying drawing, forming part thereof.

The figure is a perspective view of the design.

The design consists in the piano-case provided with the legs *a a*, which, as represented in the drawing, are right-angular in cross-section and narrowing toward their upper ends, the said legs *a a* being extended above the keyboard *b* and having at their upper ends candlestick lip-shaped saucers or receptacles,

forming candlestick or lamp holders, as indicated by *c c*.

d indicates the music-desk, shaped as shown, and *e* a shelf or ledge supporting said music-desk, the said shelf *e* being arranged at right angles to the vertical front of the piano. Underneath the shelf *e* and supporting it are arranged brackets *f f f*.

g indicates the right-angularly-formed lid of the keyboard.

I claim—

The design for a piano case herein shown and described.

WALTER CAVE.
